UNITED STATES PATENT OFFICE.

CHARLES THOMAS KEMP AND NORMAN EDWARD RYCKMAN, OF HAMILTON, ONTARIO, CANADA, ASSIGNEES TO THE COFFIELD WASHER COMPANY OF CANADA LIMITED, OF HAMILTON, ONTARIO, CANADA.

WASHING MACHINE.

Application filed May 3, 1926. Serial No. 106,490.

Our invention relates to improvements in washing machines with more particular reference to that type of machine employing a stationary tub and an oscillatory agitator 5 therein, and the object of the invention is to devise a more efficient machine by providing for a more perfect and effective movement or circulation of the water in the tub and the clothes being washed therein.

10 Our invention consists in the construction and arrangement of parts all as hereinafter more particularly described and illustrated in the accompanying drawings, in which:—

Fig. 1 is a central vertical elevation of 15 the tub and agitator of a washing machine constructed in accordance with our invention, the agitator being shown in elevation.

Fig. 2 is a side elevation of the agitator, the view being taken at right angles to that 20 of Fig. 1.

Fig. 3 is a top plan view of the agitator. In the drawings, like characters of reference indicate corresponding parts in the various views.

25 The present application relates to the tub and agitator only and therefore these parts of the machine only have been illustrated since the manner of driving the agitator is no part of this application.

30 In the form illustrated, our invention comprises a cylindrical tub 1 having the upper edge rolled at 2.

The bottom of the tub is of concave dished form at 3 and is formed with a central depression 4 which forms a sediment zone at 35 the bottom of the tub.

The bottom would be sweated onto the tub or otherwise suitably secured thereto.

The agitator 5 used in our invention comprises the flat disc-like base 6 and the central standard 7 projecting perpendicularly 40 therefrom.

This standard would be in the form of a sleeve to provide for supporting and driving the agitator from the shaft 8 as described in our copending application but as 45 this does not form part of this present application it will not be described in detail other than to say that the agitator oscillates 50 within the tub, which oscillation may be provided for in any suitable manner.

The agitator comprises four fins, 9, 9 and 10, 10.

These fins are arranged in opposed pairs,

the fins of each pair being parallel and on 55 opposite sides of the standard 7 and are further offset laterally to lie in different planes.

Each fin extends from the periphery of the base 6 and merges into the standard 7 at 60 a point adjacent to the top thereof.

Each fin comprises a lower portion A 65 standing from the base 6 and an upper portion projecting laterally from the standard 7, the profile of the lower portions A being of concavo-convex form with the convex portion outermost or nearest the periphery.

The upper portions B of the fins 9 are of substantially the same width for the greater part of their length and towards 70 the top are inclined rapidly in to the point where they merge into the standard.

The upper portions C of the fins 10 are of 75 gradually decreasing width throughout and finally merge into the standard 7.

The agitator is supported within the tub so that the base lies within the depression 4.

A drain faucet 11 communicates with an outlet orifice in the bottom of the tub and about this outlet a small depression is formed 80 in the bottom.

A lid 12 is provided for the tub and the construction of this lid is novel.

The peripheral edge of the lid 12 is rolled 85 downwardly at 13 and the lid is formed with an annular downwardly dished portion 14 in spaced relation from the peripheral edge 13 so as to form an annular recess 15 in the under face of the lid between the rolled edge 13 and the dished portion 14.

When the lid is placed in position the 90 rolled edge 2 of the tub projects into this annular recess 15.

The dished portion 14 thus extends downwardly below the top edge of the tub and 95 all splash from the under face of the lid drains directly back into the tub so that the lid is self draining and it is impossible for suds to leak over the top of the tub.

The operation of our invention is as follows:—

After the tub has been properly filled with water and clothes to be washed the agitator 5 is driven with an oscillatory motion.

Owing to the peculiar form of agitator 105 and the fins 9 and 10 thereof in combination with the dished portion 3 of the tub bottom the contents of the tub are given a

circular rolling motion as illustrated by the broken line circles in Fig. 1.

The movement is outwardly over the dished bottom 3, upwardly at the circumference of the tub and downwardly towards the center of the tub.

This not only results in a very complete and thorough circulation of the water but keeps the clothes in constant and vigorous movement, thus insuring very effective washing.

The upper portions of the fins 9 and 10 prevent the clothes from sticking close to the center of the tub and keep them out towards the outside of the tub.

From the foregoing it will be apparent that we have devised improvements in washing machines whereby the objects of our invention have been attained.

20 What we claim as our invention is:

1. An agitator for a washing machine comprising a flat disc like base, a central standard upstanding axially therefrom, four fins, each fin comprising a lower portion upstanding from the base and an upper portion projecting laterally from the standard, the marginal edges of the lower portions merging into those of the upper portions, said fins disposed in opposed pairs about the agitator, the fins of each opposed pair being similar and lying in parallel planes perpendicular to the planes of the other opposed pair, and the planes of each opposed pair offset laterally on opposite sides of the diametral plane parallel to said pair, the lower upstanding portions of all fins being similar

and of concavo-convex profile with the convex portions outermost, the upper portions of one opposed pair being of substantially uniform lateral width throughout the greater portion of their height and the upper portions of the other opposed pair being of uniformly decreasing lateral width throughout their height, the upper portions of all the fins merging into the standard at substantially the same height thereon.

2. In a washing machine, the combination with a cylindrical tub, and an agitator according to claim 1 mounted therein for oscillation about the axis of the tub, of a concave dished bottom for the tub, said dished bottom extending from the periphery of the disc like base of the agitator to the wall of the tub, the innermost portion of said dished bottom being level with the top surface of the disc like base of the agitator.

3. In a washing machine, the combination with a cylindrical tub, and an agitator according to claim 1 mounted therein for oscillation about the axis of the tub, of a concave dished bottom for the tub, said dished bottom extending from the periphery of the disc like base of the agitator to the wall of the tub, the innermost portion of said dished bottom being level with the top surface of the disc like base of the agitator, and the tub bottom formed with a depression into which the disc like base of the agitator is positioned.
